(57) **CLAIM**

The ornamental design for a helmet for sports, as shown and described.

DESCRIPTION

FIG. 1 is a front elevational view of a helmet for sports showing my new design;

FIG. 2 is a rear elevational view thereof;

FIG. 3 is a left side elevational view thereof;

FIG. 4 is a right side elevational view thereof; and,

FIG. 5 is a perspective view thereof.

The broken lines in the figures depict the portions of the article that form no part of the claimed design.
